(57) CLAIM

The ornamental design for a wine charm, as shown and described.

DESCRIPTION

FIG. 1 is a top view of a wine charm showing our new design;

FIG. 2 is a bottom view of the wine charm showing our new design; and,

FIG. 3 is a perspective view of the wine charm wherein the broken line showing of the base of a wine glass is for environmental purposes only and forms no part of the claimed design.

1 Claim, 2 Drawing Sheets

FIG. 1

FIG. 3
